UNITED STATES PATENT OFFICE.

WILHELMINA STANYO, OF CONGRESS PARK, ILLINOIS, ASSIGNOR TO BLUE BIRD FAVOR COMPANY, INC., A CORPORATION OF ILLINOIS.

DESIGN FOR A DOLL.

Application filed November 30, 1928. Serial No. 29,060. Term of patent 7 years.

To all whom it may concern:

Be it known that I, WILHELMINA STANYO, citizen of the United States, residing at Congress Park, in the county of Cook and State of Illinois, have invented a new, original, and ornamental Design for Dolls, of which the following is a specification, reference being had to the accompanying drawing, forming part thereof.

The figure is a perspective view of a doll showing my new design.

I claim:

The ornamental design for a doll, as shown.

WILHELMINA STANYO.
